[57] CLAIM

The ornamental design for a bicycle tire, as shown and described.

DESCRIPTION

FIG. 1 is a perspective view of a bicycle tire showing my new design, it being understood that the tread pattern, which is shown only over a portion of the circumference of the tire, is repeated throughout that circumference, the opposite side being substantially the same as that shown;

FIG. 2 is a side elevational view thereof;

FIG. 3 is an end elevational view thereof; and

FIG. 4 is an enlarged fragmentary developmental plan view thereof.
